UNITED STATES PATENT OFFICE.

HOMER L. DAVIS, OF EAST AURORA, NEW YORK, ASSIGNOR, BY DIRECT AND MESNE ASSIGNMENTS, OF ONE-THIRD TO MARTIN T. DEVANEY, ONE-THIRD TO FRANK H. REHLER, AND ONE-THIRD TO CHARLES K. ERNST, ALL OF BUFFALO, NEW YORK.

WEATHER-STRIP FOR DOORS.

974,242.

Specification of Letters Patent.

Patented Nov. 1, 1910.

Application filed October 23, 1908. Serial No. 459,168.

To all whom it may concern:

Be it known that I, HOMER L. DAVIS, a citizen of the United States, residing at East Aurora, in the county of Erie and State 5 of New York, have invented a new and useful Improvement in Weather-Strips for Doors, of which the following is a specification.

This invention relates more particularly 10 to weather-strips of that type which are hinged to the lower portions of doors and bear upon the door sills for closing the space between the door and its sill when the door is shut, and which, when the door is opened, 15 are raised off of the sill, thus permitting free movement of the door over the floor.

The object of this invention is to provide 20 a weather-strip of this kind which is composed of few parts of simple construction and can be made and applied at small expense, and which will be effective in operation and will not interfere with the door being opened to its full extent.

In the accompanying drawings: Figure 1 25 is a fragmentary front elevation of a door and its frame provided with a weather-strip embodying the invention. Fig. 2 is a fragmentary perspective view of the same, on an enlarged scale, showing the door slightly 30 ajar. Fig. 3 is a fragmentary vertical cross-section of the same, showing in solid lines the position of the weather-strip when the door is closed, and in dotted lines, its position when the door is opened. Fig. 4 is a 35 similar view, showing the position of the weather-strip when the door has been opened into engagement with its frame. Fig. 5 is a fragmentary horizontal section of the same, showing the door open and the end of the 40 weather-strip at the hinged side of the door engaging the door frame.

Like letters of reference refer to like parts in the several figures.

A represents a door of ordinary construction, B the door frame and C the sill therefor. The weather-strip is arranged on the inner side of the door adjacent to its lower edge and consists of a fixed cleat or strip D which is secured horizontally on the door 45 by screws or other suitable securing means, and a movable strip E which depends from the lower edge of the cleat D and is hinged thereto—so that it can swing toward and from the sill or floor. A flexible strip F

of felt or other suitable material is secured 55 to the side of the movable strip E, which is next to the face of the door, and extends downwardly a short distance beyond the lower edge of the hinged strip E. This projecting portion of the flexible strip is adapted 60 to bear on the sill and fold under the lower edge of the hinged strip E so as to effectually close the space between the same and the sill when the door is shut.

G represents a spring which tends to 65 swing the hinged strip E upwardly away from the sill or floor and hold it in the substantially horizontal raised position shown in Fig. 2 and by dotted lines in Fig. 3. This spring consists of a spring wire extending parallel with and close to the joint between the cleat and hinged strip and having oppositely bent ends g which are respectively secured to the cleat D and hinged strip E adjacent to their ends. The spring 70 rod between its bent ends extends through the knuckles of hinge leaves secured to the cleat and hinged strip, thus constituting the pivot pin or pintle for these leaves and together therewith forming the hinges H for 75 connecting the hinged strip E and cleat D. The ends of the spring wire G normally extend at such an angle to each other that the one secured to the hinged strip E will extend outwardly from the door, so that when 80 this hinged strip is swung downwardly the spring wire will be twisted or placed under torsional strain and will swing the hinged strip upwardly when permitted to do so. The spring wire thus performs the double 85 function of a hinge rod for the hinged strip and a spring for raising the same from the floor when the door is opened, and this construction serves also to hold the spring wire in place parallel with and close to the joint 90 between the two parts of the weather-strip where it will be inconspicuous and will not detract from the neat appearance of the 95 weather-strip.

A lever arm I is preferably secured at 100 one end to the end of the hinged strip E at the outer edge of the door and extends beyond the edge of the door and is adapted to engage and slide upwardly on the frame B when the door is being closed, thereby 105 swinging the hinged strip E down against the action of the spring G into its vertical position, shown in Fig. 3, in which it closes

the space between the door and its sill. As long as the door remains closed, the arm I bearing against the frame B holds the strip E in its vertical position. When the door is opened, the arm I moves out of engagement with the frame B and frees the hinged strip E which is then swung up to its raised position by the spring G. The upward movement of the hinged strip is preferably limited by a stop K secured to and projecting outwardly from the cleat D.

In order that the weather-strip may not interfere with the opening of the door to its fullest extent, the outer corner L of the hinged strip E at the end thereof next to the hinged edge of the door is cut away at an angle, see Figs. 1 and 5, so that if the door is opened far enough this inclined corner will engage the frame B and cause the hinged strip to swing downwardly to its vertical position if the door is opened any farther. The felt strip F preferably projects beyond the inclined corner of the hinged

strip E so that it will close the end of the space beneath the door. The projecting end of the felt strip also assists in turning down the hinged strip when the door is swung wide open and preventing the same from marring the frame B.

I claim as my invention:

A weather-strip for doors comprising a fixed strip secured to the door, a movable strip connected with said fixed strip and provided with a piece of flexible material, the inner end of said movable strip being cut away leaving said flexible material exposed, and means for normally holding said movable strip in a raised position, substantially as set forth.

Witness my hand, this 15th day of June, 1908.

HOMER L. DAVIS
